SHADE ROLLER

Ersyl F. Chambliss, Chicago, Ill., assignor of one-half to Joseph W. Fay, Villa Park, Ill.

Application July 25, 1934, Serial No. 736,819

17 Claims. (Cl. 156—36)

This invention relates to shade rollers of the type provided with a spiral spring for automatically winding up a shade carried thereby, and is more particularly concerned with locking mechanism for the roller, which will permit the roller to be rotated against the action of the spring, but which will lock the roller against rotation under action of the spring under certain conditions of use.

10 It is old to provide a shade roller with locking mechanism which will permit the roller to be rotated to raise or lower the shade, and which will be effective up to a certain velocity of rotation of the roller to automatically and positively 15 lock the roller against rotation when the shade is released, thereby holding the shade in any adjusted position with respect to the roller.

The chief object of the present invention is to provide an improved shade roller combining the known form of locking mechanism with a second locking mechanism, separate and distinct from the aforementioned locking mechanism, which will become effective to lock the roller against rotation should the velocity of rotation 25 of the roller rise a predetermined amount above the certain velocity of rotation of the roller at which the first mentioned locking mechanism becomes ineffective. In other words, up to a certain velocity of rotation of the roller, the first 30 mentioned locking means will be effective to hold the roller against rotation, and, at a predetermined value above said certain velocity of rotation of the roller, the second locking means will become effective to hold the roller against rotation.

The said predetermined difference in velocity of rotation represents the working range within which the two locking means are both ineffective so that the curtain may be run up by hand.

40 The foregoing object and others ancillary thereto are preferably accomplished as follows:

According to the preferred embodiment of the invention, a pair of diametrically disposed pivoted pawls are pivoted at one end to one end of 45 the shade roller for rotation therewith, these pawls, at their free ends, being adapted to engage in notches or recesses formed in the spring spindle of the roller for locking the roller against rotation with respect to the spindle. Up to a 50 certain velocity of rotation of the roller, these pawls are adapted to drop by force of gravity into the notches in the spindle and to lock the spindle to the roller, thereby holding the shade in any desired adjusted position. Above this certain 55 velocity of rotation of the roller, however,

the centrifugal force acting on the pawls will overcome the force of gravity thereon and the above locking action cannot take place. It will be apparent, therefore, that should the shade suddenly escape from the hands of a person trying 5 to adjust the same, that the shade roller would immediately rotate at a relatively great velocity, thereby winding the shade around the roller with great rapidity with probable injury to the shade and certain annoyance to the operator. To prevent this uncontrolled escape, the shade roller of the present invention has been provided with a second separate and distinct locking mechanism which will become effective to lock the roller against rotation at a velocity which is a 10 predetermined amount above the velocity of rotation of the roller at which the pawls fail to lock the roller to the spindle thereof. There must be a certain difference of running movement or velocity of the shade roller between that 15 at which the pivoted pawls become ineffective and that at which the second locking mechanism becomes effective, otherwise the shade could not be raised. This range of velocities in which the roller runs freely corresponds to the rate 20 at which the operator would raise the shade under hand control.

The second locking mechanism comprises, preferably, a double cam disc, (a single or multiple cam being contemplated), which is rigidly 30 secured to the spring spindle of the roller, this cam being disposed in a drum which is rigidly secured to the shade roller. A frictional locking roller or ball is carried by the inner surface of the flange of the drum and is adapted, upon a 35 certain velocity of rotation of the drum and roller, to become wedged between the cams and the inner surface of the flange of the drum and thereby lock the shade roller against rotation with respect to its spindle. Where the velocity 40 of rotation of the shade roller is such that the pivoted pawls are effective to lock the shade roller to the spindle, this frictional roller merely rolls along the flange of the drum, being held in the lower portion thereof by gravity. However, when 45 the velocity of rotation of the shade roller rises above that which permits the pivoted pawls to be effective, the action of the centrifugal force, which holds the pawls out of engagement with the recesses in the spindle, immediately overcomes the force of gravity which holds the friction roller in the lower portion of the drum, and the roller is carried around with the drum and wedged between the flange thereof and the cam, thereby locking the shade roller against rotation 50 55

with respect to the spindle. It will be apparent, from the foregoing, that the only free running movement of the shade roller will be in the range between the speed at which the pivoted pawls 5 become ineffective and the speed at which the cam mechanism becomes effective to lock the shade roller to the spindle. In other words, the roller must rotate above a certain limit of low speed and below a certain limit of high speed, 10 for otherwise the shade roller will be locked against rotation. With the present device, the destruction of a shade by a too fast winding thereof upon the roller is eliminated, but the shade can be wound up by a relatively slow steady 15 movement within certain limits, and if the movement of the shade is too fast or too slow, it will be locked.

The novel features that I consider characteristic of my invention are set forth with particularity in the appended claims. The invention itself, however, both as to its organization and its method of operation, together with additional objects and advantages thereof, will be best understood from the following description of a 25 specific embodiment thereof when read in connection with the accompanying drawing, in which:

Figure 1 is a longitudinal view, partly in section, through one end of a shade roller embodying the principles of the present invention;

Figure 2 is an end view of the shade roller shown in Figure 1;

Figure 3 is an end view of the cam locking mechanism taken along the line 3—3 of Figure 1 35 and showing the inoperative position of the locking mechanism; and

Figure 4 is a view similar to Figure 3, but showing the operative position of the cam locking mechanism.

Referring now in detail to the drawing, it will 40 be seen that the shade roller 10, upon which the shade 11 is adapted to be wound, is of the ordinary and well-known cylindrical form. This shade roller may be formed of wood, or of any 45 suitable metal, and is provided with an internal bore 12 for the reception of an internal spindle 13, around which is coiled a spiral spring 14. The spring 14 may be secured at one end, to the roller 10 in any suitable or preferred manner, and at 50 its other end, the spring is fastened into a slot 15 in spindle 13 so that the roller may readily rotate about spindle 13 by action of the spring 14 as is customary in spring rollers of this class.

Spindle 13 terminates closely adjacent the 55 outer end of roller 10 and is provided with a stud 16 having a reduced portion 17, which extends into a bore 18 in spindle 13 and is rigidly secured therein in any suitable or preferred manner. Stud 16 extends outwardly from the end of roller 10 and projects through a central opening 19 in a 60 flanged disc or drum 21. A flange 22 is preferably formed on the drum 21 adjacent opening 19 to provide a bearing for stud 16. This drum 65 may be formed of any suitable metal, and is disposed in abutting relation with the outer end of roller 10. Suitable tongues 23, struck out from wall 24 of the drum, are driven into the end of roller 10 and serve to rigidly secure the drum to the roller for rotation therewith.

Disposed within drum 21 is a double cam disc, 70 designated generally at 25, which may be formed of any suitable metal. This cam is rigidly secured to stud 16 for rotation therewith and is disposed on the stud closely adjacent wall 24 of drum 21. 75 The cam is in the form of a reverse curve and,

adjacent stud 16, is provided with pockets 26 and 27 disposed oppositely of the convergent cam surfaces 28 thereof. These pockets are adapted to receive frictional rollers or balls 29 and 31, respectively. The fixed cam disc 25 having a cam 5 and pocket on each side of the stud, with a roller for each pocket, the shade roller 10 may be placed in its brackets with either side 32 of flattened portion 33 of stud 16 in an upward position. As shown in the drawing, the roller 29 is seated 10 within pocket 26 of cam 25, and roller 31 is disposed beneath cam 25 and seats on flange 34 of drum 21. Roller 31 is adapted to engage the cam surface 28 of cam disc 25 and form a wedging action therebetween and the flange 34 of drum 21, 15 and thereby lock roller 10 against rotation.

Roller 31 is maintained within drum 21 and prevented from moving laterally outwardly therefrom by means of a cup-shaped disc 36. This disc, which may be formed of any suitable metal, 20 has the flange 37 thereof abutting and seating on flange 34 of drum 21. Inward movement of disc 36 is prevented by cooperating shoulders 38 and 39 formed on disc 36 and drum 21, respectively, and outward movement of disc 36 is prevented by an upturned flange 41 formed on the housing 42, the flange 37 of disc 36 abutting the inner surface of flange 41 of the housing. The housing 42, which encloses the drum 21 and disc 36, may be formed of any suitable metal and is 30 rigidly secured to roller 10 as by crimping the inner ends 43 thereof into the outer surface of the roller.

Disc 36 also serves to support two pawls 45, which are located on the disk at diametrically opposite points. These pawls are pivotally secured at one end to the disk by means of pins 46, and at their free ends, the pawls are provided with projections 47. These projections are adapted to engage in recesses 48 formed in an enlarged 40 flange or boss 49, which is rigidly secured to stud 16. As the pawls 45 are mounted on disc 36 for rotation therewith, the engagement of the projections 47 in recesses 48 of boss 49, which is rigidly secured to stud 16, will lock roller 10 45 against rotation.

The operation of the device with the various parts normally in the position shown in Figures 2 and 3, is as follows:

To cause the shade to descend, it is merely 50 pulled downwardly at a sufficient rate of speed to impart a velocity of rotation to the roller which will cause the pawls 45 to fly outwardly under the action of centrifugal force and thereby release the pawls from the recesses 48 of boss 49. 55 When the desired position of the shade is reached, the velocity of rotation imparted to the roller is reduced until one of the pawls 45 drops into one of the recesses 48, under the influence of gravity, whereupon the roller will be locked with respect 60 to spindle 13 and the shade will be held in the desired adjusted position. The roller 31 during such descending movement of the shade will remain in approximately the position shown in Figure 3 of the drawing, by reason of its own gravity, 65 and will rotate in about such position by reason of its frictional contact with flange 34 of drum 21. Likewise, to raise the shade, it is first drawn down sufficiently to disengage pawls 45 from recesses 48 of bosses 49. The tension stored up in spring 14 by downward movement of the shade will then serve to impart sufficient velocity to roller 10 to wrap the shade therearound. Also, the velocity of rotation imparted to roller 10 by 70 75

spring 14 will be such that pawls 45 will be held out of engagement with recesses 48 by centrifugal force until such time as the desired position of the shade is reached, whereupon a reduction in 5 the velocity of rotation of the roller 10 will cause one of the two pawls 45 to drop into one of the recesses 48 by gravity and thereby lock the roller against further rotation. During such ascension 10 of the shade, the roller 31 will remain in approximately the position shown in Figure 3 of the drawing, for the same reasons previously set out.

It will appear from the foregoing that in normal operation of the shade, the pawl mechanism will be effective to automatically and positively 15 lock roller 10 against rotation with respect to spindle 13. Up to a certain velocity of rotation of roller 10, therefore, pawls 45 will lock roller 10 to spindle 13. Above such velocity of rotation, however, the pawls will be ineffective, and the shade may be raised or lowered at will. This may be termed the "free-running range" of the shade. If the operator winds the shade up too fast or lets go of the shade, it will be obvious that the shade will rapidly wind itself around the roller 20 with possible destruction to the shade and annoyance to the operator. This is so, because within the free running range of the shade, pawls 45 are ineffective to lock roller 10 to spindle 13. To overcome this difficulty, the free running range 25 of the shade has, therefore, been confined within certain limits by the pawls 45 and the cam locking mechanism. If the shade is permitted to rise too fast, or if the operator lets go of the shade, roller 10 will have a velocity of movement 30 such that the centrifugal force which tends to hold pawls 45 out of engagement with recesses 48 on the stud 16, will also be effective to carry roller 31 around with drum 21 and into wedging locking engagement with cam surface 28 of cam 35 25, and flange 34 of drum 21. The roller 31 and cam 25 will then be in the position shown in Figure 4 of the drawing, and roller 10 will be locked to spindle 13 against rotation. The amount of free running range permitted the 40 shade will of course depend upon the design of cam 25. The cam may be designed so that roller 31 has relatively little movement with respect to the cam, in which case the cam mechanism will become effective almost immediately the pawl 45 mechanism becomes ineffective, or roller 31 may have a relatively large amount of movement with respect to cam 25, in which case the free running speed of the shade will also be relatively large. To release roller 31 from locking engagement with cam 25, as shown in Figure 4 of the drawing, the shade is merely pulled downwardly, thereby rotating drum 21 in a counter-clockwise direction, in which case roller 31 is carried out of engagement 45 with cam 25 by drum 21.

From the above, it will appear that with the present device, the roller must rotate above a certain limit of low speed and below another limit of high speed, for otherwise the roller will be locked against rotation for winding up the shade. Thus, 50 the roller will be locked if the operator is careless or neglectful in attempting to wind the shade up too fast. With the present arrangement, the destruction of the shade by a too fast winding thereof upon the roller is eliminated, but the shade can be wound up by a relatively slow, steady movement within certain limits, and if the movement of the shade is too fast, it will be locked.

Although I have shown and described a preferred embodiment of my invention, I am fully aware that many modifications thereof are possi-

ble. My invention, therefore, is not to be restricted except in so far as is necessitated by the prior art and by the spirit of the appended claims.

What is claimed is:—

1. The combination with a spring shade roller, of a non-rotatable spindle for said roller, means associated with said roller and spindle for positively and automatically locking said roller to said spindle when the speed of said roller is maintained below a certain low velocity, and normally inactive locking roller and cam means associated with said shade roller and spindle and separate from said first named locking means which becomes active to lock said shade roller to said spindle when the speed of said roller exceeds a certain high velocity and the first named locking means has become ineffective.

2. The combination with a spring roller of a non-rotatable spindle for said roller, pawl means associated with said roller and spindle for positively and automatically locking said roller to said spindle when the speed of said roller is maintained below a certain low velocity, and locking roller and cam means associated with said spindle and shade roller and separate from said pawl means to lock said roller to said spindle when the speed of the roller exceeds a certain high velocity and the pawl means becomes ineffective.

3. The combination with a spring roller, of a non-rotatable spindle for said roller, a plurality of pawls associated with said roller for rotation therewith, a boss secured to said spindle and having a plurality of recesses therein, said pawls engaging in said recesses to positively and automatically lock said roller to said spindle when the speed of said roller is maintained below a certain low velocity, and cam and roller means associated with said spindle and shade roller and separate from said pawls to lock said roller to said spindle when the speed of the roller exceeds a certain high velocity and the pawls become ineffective.

4. The combination with a spring roller, of a non-rotatable spindle for said roller, means associated with said roller and spindle for positively and automatically locking said roller to said spindle when the speed of said roller is maintained below a certain low velocity, a drum associated with said roller for rotation therewith, and locking roller and cam means associated with said drum and said spindle for locking said drum to said spindle when the speed of said roller and drum exceeds a certain high velocity and the first named locking means becomes ineffective.

5. The combination with a spring roller, of a non-rotatable spindle for said roller, means associated with said roller and spindle for positively and automatically locking said roller to said spindle when the speed of said roller is maintained below a certain low velocity, a drum associated with said roller for rotation therewith, a cam carried by said spindle, and locking roller means cooperating with said drum and said cam for locking said spindle to said roller when the speed of said roller exceeds a certain high velocity and the first named locking means becomes ineffective.

6. The combination with a spring roller, of a non-rotatable spindle for said roller, means associated with said roller and spindle for positively and automatically locking said roller to said spindle when the speed of said roller is maintained below a certain low velocity, a drum associated with said roller for rotation therewith, a cam carried by said spindle, and a roller member

disposed in said drum and adapted for wedging locking engagement with said drum and cam to lock said spring roller to said spindle when the speed of said roller exceeds a certain high velocity and the first named locking means becomes ineffective.

7. The combination with a spring roller, of a non-rotatable spindle for said roller, means associated with said roller and spindle for positively 10 and automatically locking said roller to said spindle when the speed of said roller is maintained below a certain low velocity, a drum having an annular flange associated with said roller for rotation therewith, a cam carried by said spindle, 15 and a roller member disposed in said drum and seating on the flange thereof, said roller member being adapted to have wedging locking engagement with said cam and the flange of said drum to lock said spring roller to said spindle when the speed of said roller exceeds a certain high velocity 20 and the first named locking means becomes ineffective.

8. The combination with a spring roller, of a non-rotatable spindle for said roller, means associated with said roller and spindle for positively 25 and automatically locking said roller to said spindle when the speed of said roller is maintained below a certain low velocity, a drum having an annular flange associated with said roller for rotation therewith, a cam carried by said spindle, 30 and a roller member disposed in said drum and seating on the flange thereof, said roller member being normally inactive when the speed of the spring roller is maintained below a certain low velocity, and becoming active to move into wedging locking engagement with said cam and the flange on said drum and thereby lock said spring roller to said spindle when the speed of said roller exceeds a certain high velocity and the 35 first named locking means becomes ineffective.

40 9. The combination with a spring roller, of a non-rotatable spindle for said roller, means associated with said roller and spindle for positively and automatically locking said roller to said spindle when the speed of said roller is maintained below a certain low velocity, a drum having an annular flange associated with said roller for rotation therewith, a double cam having a plurality of pockets therein carried by said spindle, a plurality 45 of locking rollers disposed in said drum, one of said rollers normally seating in one of said pockets and another of said rollers normally seating on the flange of said drum in each of two diametrically opposite positions of the spring 50 roller, said locking roller member being adapted to have wedging locking engagement with said cam and the flange of said drum to lock said spring roller to said spindle when the speed of said spring roller exceeds a certain high 55 velocity and the first named locking means becomes ineffective.

60 10. The combination with a spring shade roller of a non-rotatable spindle for said roller, locking means comprising a drum secured to said roller for rotation therewith, a cam secured to said spindle, wedging means disposed in said drum and cooperating with said drum and said cam for locking said roller to said spindle when the speed of said roller exceeds a certain high velocity, 65 means disposed in said drum for retaining said wedging means therein, and means associated with said last named means and said spindle to lock said roller to said spindle when the speed of said roller is below a certain low velocity.

75 11. The combination with a spring shade roll-

er of a non-rotatable spindle for said roller, a stud secured to said spindle and extending outwardly therefrom, locking means comprising a drum secured to said roller for rotation therewith, a cam secured to said spindle, wedging means disposed 5 in said drum and cooperating with said drum and said cam for locking said roller to said spindle when the speed of said roller exceeds a certain high velocity, means disposed in said drum for retaining said wedging means therein, a plurality 10 of pivoted pawls carried by said last named means, and a boss having recesses therein secured to said stud, said pawls engaging the recesses in said boss under the influence of gravity to lock said roller to said spindle when the speed of said roller is 15 below a certain low velocity.

12. The combination with a spring shade roller of a non-rotatable spindle for said roller, a stud secured to said spindle and extending outwardly 20 therefrom, locking means comprising a drum secured to said roller for rotation therewith, a cam secured to said spindle, wedging means disposed in said drum and cooperating with said drum and said cam for locking said roller to said spindle when the speed of said roller exceeds a certain 25 high velocity, a flanged disc disposed in said drum for retaining said wedging member therein, cooperating means on said disc and said drum for restraining lateral inward movement of said disc with respect to said drum, a plurality of pivoted 30 pawls carried by said disc, and a boss having a plurality of recesses therein secured to said stud, said pawls engaging the recesses in said boss under the influence of gravity to lock said roller to said 35 spindle when the speed of the roller is below a certain velocity.

13. The combination with a spring shade roller of a non-rotatable spindle for said roller, a stud secured to said spindle and extending outwardly 40 therefrom, locking means comprising a drum secured to said roller for rotation therewith, a cam secured to said spindle, wedging means disposed in said drum and cooperating with said drum and said cam for locking said roller to said spindle when the speed of said roller exceeds a 45 certain high velocity, a flanged disc disposed in said drum for retaining said wedging member therein, cooperating means on said disc and said drum for restraining lateral inward movement of said disc with respect to said drum, a housing 50 secured to said spring roller, an inturned flange on said housing, said flange cooperating with the flange of said disc to restrain lateral outward movement of said disc with respect to said drum, a plurality of pivoted pawls carried by said disc, 55 and a boss having a plurality of recesses therein secured to said stud, said pawls engaging in said recesses under the influence of gravity to lock said roller to said spindle when the speed of the roller is below a certain velocity.

14. The combination with a spring shade roller of a non-rotatable spindle for said roller, a stud secured to said spindle and extending outwardly 60 therefrom, locking means comprising a drum having an annular flange secured to said roller for rotation therewith, a cam secured to said spindle, a roller member disposed in said drum and seating on the flange thereof, said roller member being normally inactive when the speed of the roller is maintained below a certain low 65 velocity and becoming active to move by centrifugal force into wedging locking engagement with said cam and the flange on said drum and thereby lock said spring roller to said spindle when the speed of said spring roller exceeds a 70

certain high velocity, means disposed in said drum for retaining said roller member therein, a plurality of pivoted pawls carried by said last named means, and a boss having recesses therein secured to said stud, said pawls engaging the recesses in said boss under the influence of gravity to lock said roller to said spindle when the speed of said roller is below a certain low velocity.

10 15. In combination, a spindle with a flattened end having two positions of engagement with a bracket and held against rotation thereby, a shade roller rotatable with respect to said spindle, and means comprising a cam member on the spindle and cooperating wedging means operable in each position of said spindle in said bracket for preventing too rapid rolling of said shade up on said roller.

16. In combination, a spindle with a flattened end having two positions of engagement with a bracket and held against rotation thereby, a shade roller rotatable with respect to said spindle, a cam member held against rotation by said

spindle and having a pair of cam portions, and a pair of locking roller members carried by said shell member, one of said roller members being cooperable with one of said cam portions in each of the positions of said spindle in its bracket whereby to lock the roller against rotation at too rapid speed in the direction in which the shade is rolled up on said roller.

17. In combination, a spindle with a flattened end having two positions of engagement with a bracket and held against rotation thereby, a shade roller rotatable with respect to said spindle, a shell secured to the end of the roller for rotation therewith, a cam member on the spindle, wedging means carried by said shell member and cooperable with said cam member to lock said roller against too rapid rotation in either of the two positions of said spindle in said bracket, a member for retaining said wedging means in said shell, and means carried by said last member for locking said roller to said spindle when the speed of said roller is relatively low. 10 15 20

ANSWER TO RELATIVE TO
ERSYL F. CHAMBLESS.
